UNITED STATES PATENT OFFICE.

LUTHER C. SNELL, OF DETROIT, MICHIGAN, ASSIGNOR TO THE LIQUID SUPPLY COMPANY, OF OLEAN, NEW YORK.

DEVICE FOR BURNING CRUDE PETROLEUM.

SPECIFICATION forming part of Letters Patent No. 446,796, dated February 17, 1891.

Application filed July 25, 1890. Serial No. 359,857. (No model.)

To all whom it may concern:

Be it known that I, LUTHER C. SNELL, a citizen of the United States, and a resident of Detroit, in the county of Wayne and State of Michigan, have invented certain new and useful Improvements in Devices for Burning Crude Petroleum; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my new and improved burner or device for burning crude petroleum. Fig. 2 is a side view taken from the front side, with the hinged door or side thereof swung down in its open position. Fig. 3 is an end view of the same. Fig. 4 is a transverse vertical sectional view taken on line $x-x$, Fig. 2. Fig. 5 is a longitudinal vertical sectional view taken on the plane indicated by the line $y-y$ of Fig. 4, and Fig. 6 is a detail view of the evaporating-pan removed from the device.

The same letters of reference indicate corresponding parts in all the figures.

My invention consists in a new and improved device or burner for burning crude petroleum for fuel in stoves or furnaces, by the use of which burner a pure white light of dazzling brilliancy and any required degree of heat is obtained from crude petroleum; and my invention will be hereinafter fully described and claimed, referring to the several parts by letter.

In the accompanying drawings I have shown my new and improved burner constructed in a square or rectangular form, although it may be constructed either round or half-round, as hereinafter more fully specified, or in any other shape to fit the stove to which it is to be attached.

A indicates the bottom plate of my new and improved device, which is thickly provided with the perforations α , and which has around three of its sides the downwardly-projecting rim-flange B, which serves to raise the perforated bottom A clear above the surface on which the device is resting to permit of the

free entrance of air through the perforated bottom.

The ends CC of the device are formed with the large end openings D D, and the rear side of the device is formed with a double or hollow wall, the inner wall or side E being thickly provided with perforations F, like those of the bottom A, while the outer wall G and the top of the device are both solid—that is, are without perforations.

The end walls C C of the device, which close the ends of the space between the double walls E and G, are likewise formed with perforations H, for the purpose hereinafter specified.

The upper ends of the inner wall E are formed with the openings I I, which may be square, as here shown, or of any other suitable form, and with these openings communicate the inner or rear ends of ducts or tubes J K, which extend along the inner upper ends or corners of the device, as shown, from the rear inner wall E to the front wall or side of the device, where their front or outer ends communicate or register with openings of the same size cut or formed in the upper corners of the hinged door or side piece L, the lower and upper sides of these tubes J K being formed with numerous perforations M, as shown. The outer walls of said ducts J and K are also perforated.

N indicates an elevated reservoir for the petroleum, from which the supply-pipe O leads to the top of the device, the flow of oil through the said pipe into the evaporating-pan of the device being regulated by the stop-cock P.

The inner end of the supply-pipe from the oil-reservoir enters through the small dome T of the top of the device and communicates with an opening U, leading from the raised dome down through the top of the device.

V indicates the evaporating-pan, which is usually in this form of burner rectangular in shape, being formed with the rather deep ends and sides and having formed through its central portion the longitudinal opening W, around which extends the shallow rim or upwardly-projecting flange X, which is not one-half the height of the outer end and side pieces of the pan. This evaporating-pan is

secured in operative position within the device against the under side of the solid top thereof, with the upper edges of its sides and ends in contact with the under or lower surface of the solid top of the device, its front side being in contact with the hinged door L, while its rear side is in contact with a downwardly-projecting solid flange Y at the rear of the top of the device, as shown in Fig. 4 of the drawings, and in this position the lower end of the opening U, through which the oil passes through the top of the device, is to one side of the central opening W of the evaporating-pan. Beneath, to the bottom of the evaporating-pan, and extending transversely across the same, is secured the air-flue A', the inner rear end of which rests upon a strip or bearing B' on the inner perforated wall E, so that it is thus supported while it communicates with a longitudinal opening C' in the said inner wall, while the front end of this flue communicates or registers with a longitudinal opening D' of the same size in the central part of the hinged door or side piece L at the front side of the device. When the evaporating-pan, and with it the air-flue, which is secured to its lower side, is placed in position, the lower inner or rear end of the air-tube rests upon the bar or bearing-strip B' and the inner end of the flue and also that end or side of the evaporating-pan, while the outer side of said pan is supported and held up in operative position by means of a catch E', consisting of a wire bail having vertical arms secured to said dome at their upper ends and a horizontal portion E², which engages with a projection F', secured to the evaporating-pan. (See Fig. 2.) The pan being thus secured in position, the hinged perforated door L is closed, and is held in its closed position by means of the catch G'.

The central opening W of the evaporating-pan is provided with the downwardly-projecting flange or tube II', the lower end of which extends down in very close proximity to the plane of the upper surface of the bottom of the air-tube A', while immediately beneath and registering with this central longitudinal opening in the bottom of the evaporating pan a longitudinal opening I' is formed centrally in the bottom of the air-tube A', and this opening, which is larger than the bottom opening of the evaporating-pan, is provided with a downwardly-projecting flange or tube J', which extends down to within a suitable distance from the shallow drip-pan K', which rests upon the bottom A of the device below the said tube and openings.

In operation the burner here shown is placed in a cook-stove, (shown in dotted lines in Figs. 2 and 4,) the front doors of the said stove being opened, with the front of the burner at the door of the stove, and all the openings or crevices around the burner are closed up tightly with fire-clay or other suitable substance, so that the air can enter the stove only through the burner, and not through any

openings or crevices around the same. To light the fire the stop-cock is partly turned to enable a little oil to run from the reservoir 70 down into the evaporating-pan, which it fills until it overflows the shallow rim X, which projects up around the edges of the central opening W in the bottom of the evaporating-pan, when it runs down through the central 75 registering opening in the bottom of the said pan and the air-flue and falls into the shallow drip-pan K', where it is lighted with a match. The fire thus kindled soon heats the evaporating-pan so that it converts all the oil which 80 flows into it into vapor and sends vapor only down through its central opening and the downwardly-projecting flange or tube II' of the same, where the vapor is mixed with the current of air which is drawn through both 85 ends of the air-flue, the currents of air being indicated by the short thick arrows and the currents of vapor by the long curved arrows. The air enters the front end of the air-flue through the opening D' of the hinged front 90 door L, and also through the open front ends of the flues or tubes J K, passing through the said tubes and into the rear air-chamber formed by the double rear walls, and whence it passes into the rear end of the air-flue A', and the 95 mixed vapor and air is drawn by the draft down through the central opening and tube, where it is ignited by the fire lighted in the drip-pan, and thus shoots a continuous flame at the drip-pan, as will be readily understood, 100 as long as any oil is allowed to flow into the evaporating-pan, which, as described, is over the fire and continues to be kept hot by the fire. The downwardly-pouring flame divides over the drip-pan and passes out into the fire-box of the stove through the large end openings D D of the burner, passing out through the ends of the burner in a snow-white flame of the most dazzling brilliancy and of great heat. 105 Thus it will be seen that the burning gas receives air all the way from the point where it passes out at the bottom of the flue A' and until it escapes into the fire-box of the stove, receiving it mainly from the hollow space between the double rear walls of the device, for 110 as the burning vapor divides at the bottom of the flue and passes along through the burner toward each end of the same to the end openings D D it draws air from the large air-chamber formed by the double rear walls 115 through the perforated inner wall E thereof, through the perforated ends C C, and through the perforated lower sides and outer sides of the two air-tubes J and K, the only air received except through the perforations being 120 when the air is mixed with the vapor as it passes down through the central opening of the air-flue, the air entering through both ends of the air-flue, as before described. Slots could be used in lieu of the perforations in 125 the several parts, as will be readily understood.

From the foregoing description, taken in connection with the accompanying drawings,

the construction, operation, and great advantages of my new and improved device for burning crude petroleum will be readily understood.

5 It will be seen that my invention is simple and strong in construction and efficient in its operation. The fundamental principle of my invention is the feeding of the oil into a heated evaporating chamber or pan, in which 10 it is held until evaporated or converted into vapor, which lighted is then drawn by the draft of the stove through a space forming the fire-box and having perforated walls through which air is drawn to mix with the 15 vapor, the air being supplied from the room in which the stove stands.

My improved device can be applied to any stove, with slight modifications to suit any special construction. When it is desired to 20 set this device in a stove that has no door for the device to face, it is necessary to employ conducting-pipes to conduct the air from the opening of the stove to the air chamber or chambers of the device. When it is used in 25 a round heater or stove, the device may be made either round or half-round and the air-feed chamber extend around the evaporating-pan and receive its air from openings into the stove above the device. A round 30 drip-pan would be used with this form, and the usual perforated plate for it to sit upon; also, in some stoves it will be necessary to dispense with the air-flue altogether, as, before mentioned, it covers so much of 35 the bottom of the evaporating-pan, and conducts a stream of cold air against it, so that heat enough to evaporate the oil would not be obtained where the stove is not large enough to allow of the evaporating-pan projecting beyond the flue sufficiently to secure 40 a suitable or sufficient amount of heat. The evaporating-pan and also the drip-pan are both removable, as shown, for convenience in cleaning them, which will be necessary for 45 the evaporating-pan about once in two weeks when in constant use, and the tapering thimble R, which will catch impurities in the oil and prevent them from passing into the evaporating-pan, can be readily removed to 50 be cleaned.

Having thus described my invention, what I claim, and desire to secure by Letters Patent, is—

1. A device for burning crude petroleum, 55 consisting of the combination of a casing, one wall of which is hollow, an evaporating-pan within the casing, above the combustion-chamber, and provided with a downwardly-extending outlet opening into the combustion-chamber, an air-flue communicating with the outside air through one of the walls of the casing at one end and with the hollow wall of the casing at the other end, and the middle of the flue communicating with the 60 combustion-chamber at the outlet of the

evaporating-pan, the casing being provided with an outlet for the escape of the gases, &c.

2. A device for burning crude petroleum, consisting of the combination of a casing, one wall of which is hollow, the inner side of 70 which hollow portion is perforated, an evaporating-pan within the casing, above the combustion-chamber, the outlet of which is downward and communicating with the combustion-chamber, a flue communicating with the 75 combustion-chamber at the outlet of the evaporating-pan, and tubes above the outlet of the casing, the bottoms of which are perforated, each of the said tubes communicating with the outside air through one wall of 80 the casing at one end and with the hollow portion of the casing at the other end.

3. A device for burning crude petroleum, consisting of a casing having a depending flange around its bottom and having one of 85 its walls hollow, the bottom of the casing, the flange, and the inner side of the hollow portion of the casing being perforated, and an evaporating-pan within the casing, above the combustion-chamber, the outlet of which is 90 downward and communicates with the combustion-chamber.

4. A device for burning crude petroleum, consisting of the combination of a casing, one wall of which is hollow, the inner side of 95 the hollow wall being provided with an opening near its middle and an opening at the upper corner of each end, a hinged door upon the opposite side of the casing, provided with a central opening and an opening at each of 100 its upper corners, an evaporating-pan within the casing, an air-flue secured to the bottom of the pan, the ends of which communicate with the central opening in the side and in the door of the casing and its middle with 105 the outlet of the evaporating-pan, and a flue at each end of the casing communicating at their ends with the upper portions.

5. A device for burning crude petroleum, consisting of the combination of a casing, one 110 wall of which is hollow and provided with an opening, a flange upon the inner side of the hollow casing and below the lower edge of the opening, an evaporating-pan within the casing, an air-inlet flue upon the bottom of 115 the pan, the rear end of which rests upon the flange on the hollow wall and communicates with the opening, a hook upon the opposite side of the casing and adapted to engage with and support the evaporating-pan, and an 120 air-flue communicating with the hollow wall of the casing, there being an air-outlet for the escape of the vapor and air.

6. A device for burning crude petroleum, consisting of the combination of a casing, an 125 evaporating-pan within the casing, having a flange which projects above the inner surface of the bottom of the pan and below the lower surface and having an opening in the bottom, an air-flue secured to the bottom of the pan 130

and having a hole in its bottom, said hole registering with the outlet of the pan, and a flange around said hole, said casing being provided with outlets for the escape of vapor and air.

7. A device for burning crude petroleum, consisting of the combination of a casing, an evaporating-pan removably secured at its rear end to one side of the casing and provided with a projection upon the opposite end, a catch upon the side of the casing adapted to engage with the projection, and a flange secured to the top of the casing near the opposite wall, adapted to engage with the inner wall of the evaporating-pan.

15 8. A device for burning crude petroleum,

consisting of the combination of a casing having an opening at its top, a removable evaporating-pan within the casing, having a central opening and having an upwardly-projecting rim around the opening of the pan, an oil-pipe leading into the casing and opening to one side of the opening in the pan, and a drip-pan below the opening.

In testimony that I claim the foregoing as 25 my own I have hereunto affixed my signature in presence of two witnesses.

LUTHER C. SNELL.
